NEUTRALIZING APPARATUS

Filed March 25, 1930

UNITED STATES PATENT OFFICE

WILLIAM H. CHAPMAN, OF PORTLAND, MAINE, ASSIGNOR TO CHAPMAN ELECTRIC
NEUTRALIZER COMPANY, OF PORTLAND, MAINE, A CORPORATION OF MAINE

NEUTRALIZING APPARATUS

Application filed March 25, 1930. Serial No. 438,682.

In order to control the electro-static charges on moving sheets of paper or fabric in the course of its manufacture or printing, it has been customary to provide a discharge 5 bar adjacent the moving sheets and to so connect such bar in an electric system as to neutralize the static electricity generated in the process of manufacturing or printing the sheets. I have personally invented and 10 patented several types of discharge bars for this purpose which have become practically standard in the art.

The application of the discharge bar, however, to the machine with which it is intended to be used, as for example, a printing press with a fly stick delivery, is complicated by the construction of the machine itself and by the character of the initial electro-static charge on the sheets of paper or other material.

In the case of the printing press with fly stick delivery, for example, the physical presence of the widely moving fly sticks frequently prevents the location of the discharge bar at the most favorable point with reference to the sheets of paper or other material. Moreover, the sheets sometimes take on an additional charge due to some subsequent manipulation of the sheets, as for example, their passage over the fly sticks, and this additional charge introduces a further factor of complication.

Together, all of these conditions contribute toward the difficulty of leaving the paper 35 neutral at the point of delivery from the printing press or other machine. At the same time, there are certain factors in the physical construction and arrangement of the discharge bar which are capable of improvement to the end that a more satisfactory and efficient bar may be obtained. In particular, these relate to the mounting of the bar for adjustment relative to the paper 40 whereby through such adjustment the character of the charge originally carried by the paper or any additional imparted thereto in some subsequent manipulation of the paper may be neutralized, and also to the 45 construction and mounting of the discharge

points with which the bar is provided at a plurality of spaced intervals.

To the end, therefore, of improving and simplifying the construction and operation of such discharge apparatus so that a more efficient and reliable apparatus may be provided, I have devised my present invention. According to it the discharge bar carrying the discharge points and the ground bar are capable of both a pivotal and a rotative adjustment relative to the paper or other material and in addition the ground bar is capable of an independent adjustment relative to the discharge bar and discharge points. By reason of such adjustment, the apparatus may be adapted to meet any service condition.

In the accompanying drawings I have shown a preferred embodiment of my invention together with several modifications 70 which are suggestive of the many departures which may be made within the spirit and scope of my concept. In the drawings:

Fig. 1 is an elevation, partly broken away, of a neutralizing apparatus in accordance 75 with my general concept.

Figs. 2 and 3 are cross sectional details on the lines 2-2 and 3-3 respectively, of Fig. 1, and

Figs. 4 and 5 are details illustrating modified methods of mounting the discharge points.

I have indicated at 1 any usual tie rod on a printing press or other machine and at S the sheets of paper, fabric or other material 80 which are to be neutralized as to any electro-static charge which they may have or may acquire.

Clamped as at 2 to the tie rod 1, preferably adjacent each end thereof, is an arm 3. The 85 arms 3 at their opposite ends carry hinge clamps 4 adapted to be tightened or loosened as at 5 about the neutralizer bar.

Such bar comprises an inner core or rod 6 of steel or any other good conductor adapted 90 to be electrically connected at one end as at 7 to any suitable current source whereby a high tension charge of alternating current is passed into the rod, and at its opposite end 95 insulated in any suitable manner, as by a dead 100

end cap 8 of hard rubber or other appropriate insulating material screwed on or otherwise mounted on the rod 6 as by means of the threaded stud 9.

5 The hinged clamps 4 are insulated from the bar 6 by bushings B of any suitable insulating material, as wood. These bushings are split, as shown in Fig. 2, and intermediate of their ends are circumferentially grooved 10 as indicated at B¹ to receive soft rubber bands B² which when the clamps 4 are opened retain the bushings in place on the rod.

Sleeved about the conductor rod 6 is an insulating sheath in the form of a tube 10, Fig. 15 3, of rubber or the like encased in any suitable protective sheath, as the fibre tube 11. In assembling these elements, the rubber tube 10 is first coated with some substance which has the combined properties of lubricating 20 the parts so as to permit the fibre tube 11 to be slid on over the rubber tube 10 and on drying and hardening acting as an adhesive to firmly hold the two tubes against relative movement. For such a coating I may conveniently use ordinary rubber cement which before drying acts as an effective lubricant but on drying firmly binds the tubes together.

Suspended from the discharge bar 6 is a metal ground bar 12 by means of which the 30 charge on the paper transmitted to said ground bar through the ionized atmosphere surrounding the discharge bar 6 may be conveyed to ground as at 12¹. The ground bar is rotatively adjustable with reference to the 35 discharge bar, such adjustment being independent of the adjustment of the bars 6 and 12 as a unit permitted by the hinge clamps 4, the ground bar 12 for the purpose of this independent adjustment being suspended 40 from the discharge bar 6 by special clamps 13 which permit and hold such adjustment.

These clamps are detailed in Fig. 3, and are of suitable insulating material, as fibre. Each comprises a pair of jaws 13 clamped together intermediate of their ends by a screw 45 or the like as at 14 and shaped at their upper ends to define a recess of proper diameter to receive the discharge bar 6 and at their lower ends a similar recess to receive the ground 50 bar 12. The jaw fastenings 14 may be conveniently provided with wing nuts, if desired, to facilitate adjustment of the jaws.

Suspended from the discharge bar at 55 spaced intervals therealong is a plurality of discharge points. These may be mounted in any suitable manner on the discharge bar. A preferred method of mounting is detailed in Fig. 3 wherein it will be noted that I place over the outermost tube 11 a plurality of 60 loosely fitting sleeves 15 of fibre or other suitable insulating material each of which is tapped and threaded as at 16 detachably to receive a plug 17 within which is anchored one end of a helix 18 of spring wire or the like. Such helix projects downwardly be-

yond the plug and terminates in a discharge point 19 adapted to radiate the alternating charge onto the surface of the paper sheets S. This construction permits ready removal of a discharge point for purposes of replacement or renewal when desired.

70 In the modification of Fig. 4, the insulating sleeve 20 which fits over the tube 11 is tapped and threaded to receive an attaching screw 21 of hard rubber or the like. Interiorly, the sleeve 20 is circumferentially grooved as at 22 to receive segmental plates 23 of metal or other conductive material which are apertured to receive the discharge points 18. The inner ends of said discharge points are headed to prevent them from dropping through the apertures in the sleeve 20.

75 While preferable for some installations, this type of discharge point requires that the sleeve 20 be removed endwise from the tube 11 in order to permit replacement of a discharge point.

80 As a further alternative method of mounting the discharge points on the bar 6, I may use the construction shown in Fig. 5, wherein the fibre sleeve 15 is tapped and threaded to receive a plug 24 of hard rubber or the like within which the discharge points 18 are 85 mounted. Set against the upper end of each discharge point is a copper or other conductive disc 25 which transmits the charge induced by alternating charge in the bar 6 to the discharge point.

85 From the foregoing, it will be seen that I provide for a three-way adjustment of the discharge apparatus with reference to the plane of the paper S, viz., an adjustment towards and away from the paper, as indicated by the arrow V, in Fig. 3, accomplished by swinging the apparatus as a unit about the tie rod 1 as an axis; a rotative adjustment of the apparatus as a unit accomplished by loosening the clamps 4 and rotating the entire apparatus within the same, as indicated by the arrow R in said figure; and an independent arcual adjustment of the ground bar 12 relative to the discharge bar 6 accomplished by loosening the clamps 13 and rotating the ground bar with the same, as indicated by the arrow A in said figure.

90 These adjustments enable me to accommodate the apparatus to any particular set of conditions, whether caused by some structural feature of the printing press or other machine to which the apparatus is applied, or to some peculiar condition of charge of the moving sheets S.

95 Various other modifications in the construction and operation of my device may obviously be resorted to, all without departing from the spirit of my invention if within the scope 100 of the appended claims.

105 What I therefore claim and desire to secure by Letters Patent is:

110 1. In apparatus for neutralizing the static 100

electricity of a moving sheet, a fixed support, a discharge bar clamped to said support, and a ground bar clamped to said discharge bar, and a plurality of discharge points suspended from said discharge bar, the clamp connection of the discharge bar with said support permitting the discharge bar and with it the ground bar and discharge points to be rotatively adjusted as a unit relative to the sheet, and the clamp connection of the ground bar with the discharge bar permitting said ground bar to be rotatively adjusted independently of said discharge bar and discharge points.

15 2. Apparatus for neutralizing the static electricity on a moving sheet, comprising a discharge bar, an insulating sleeve on said bar having a socket, a plug of conductive material in said socket, and a discharge point in
20 said plug.

In testimony whereof I affix my signature.
WILLIAM HENRY CHAPMAN.
